ORLANDO LEE ALBERTSON, OF RICHMOND, VIRGINIA, ASSIGNOR OF THREE-FOURTHS TO
CHARLES H. REID, OF RICHMOND, VIRGINIA.

CAR-COUPING.

No. 901,863.

Specification of Letters Patent.

Patented Oct. 20, 1908.

Application filed November 18, 1907. Serial No. 402,618.

To all whom it may concern:

Be it known that I, ORLANDO LEE ALBERTSON, a citizen of the United States, and a resident of Richmond, in the county of Henrico and State of Virginia, have invented certain new and useful Improvements in Car-Couplings, of which the following is a specification.

This invention is an improvement in car 10 couplings of the twin-jaw type; and the invention consists in certain novel constructions and combinations of parts as will be hereinafter described and claimed.

In the drawing Figure 1 is a perspective view of the invention. Fig. 2 is a detailed perspective view of the lever for opening the pivoted jaw or knuckle. Fig. 3 is a detail perspective view showing the pivoted jaw or knuckle, the coupling pin, and the 20 lever for opening the jaw in the position such parts occupy when the jaw is closed. Fig. 4 is a similar view of the same parts in the position they occupy when the jaw is partially opened. Fig. 5 is a vertical longitudinal section of the coupling on about line 25 5-5 of Fig. 6. Fig. 6 is a horizontal section of the coupling with the parts in the position they occupy when the jaw is closed, and Fig. 7 is a similar view showing the 30 pivoted jaw or knuckle open.

The coupling comprises the draw-head A having the fixed jaw B and the pivoted jaw or knuckle C, which latter is pivoted at C' and has the shank C² grooved or recessed along its rear face at its upper edge at C² to form a bearing for the lug E' depending from the swinging front end of the arm E² of the jaw-opening lever E, presently described. The shank C² also has 35 at its swinging end an inclined surface at C⁴, which rides below a shoulder on the coupling pin.

The draw-head A has a bottom wall A' and a top wall A², and the latter is provided alongside the pin-opening A³ with an upwardly projecting chamber A⁴, which communicates at its lower end with the interior of the draw-head and receives the upwardly projecting pivot portion E⁴ of the 40 lever E. This pivot portion, it will be noticed projects upwardly above the arm E², which latter operates directly below the top wall A² of the draw-head, and the pivot portion E⁴ is rounded on its front face at 45 E⁵ to bear against the front wall of the

chamber A⁴, and the lever is pivotally held on a bolt F extending upwardly through the pivot portion E⁴ and thence up through the top wall of the chamber A⁴ and suitably secured. The opening lever E is also provided with a short arm E⁶ projecting toward the coupling pin G, and having at its extremity a projecting reduced portion E⁷, which operates in a recess G' in the side of the coupling pin G above the shoulder G², which is engaged by the inclined portion C⁴ of the knuckle C. This recess G' has at its lower end an inclined surface or cam G³ which engages with the lever arm E⁶ when the pin G is raised to its uppermost position, and adjusts the lever E from the position shown in Fig. 6, to that shown in Fig. 7, so that the arm E² of the lever will throw the pivoted jaw or knuckle to open position. The recess G' also has an upper inclined surface G⁴ located directly above the cam G³ and engaging with the arm E⁶ of the lever E, when the parts are in the position shown in Figs. 3 and 6, thus positively readjusting the lever E to the position shown in Fig. 6, against the wall of the draw-head.

The cam surface G³ is so arranged relatively to the arm E⁶ of the lever E, that it will not operate upon said arm until after the pin G has reached a position in which it releases the knuckle C so that in operation, as the pin G is lifted, the said pin will first release the pivoted jaw or knuckle and will then on its further movement operate on the arm E⁶ of the lever E to positively throw the knuckle to open position. It will also be noticed that if at any time the knuckle C should be released and partially opened, the pin G may be lifted to operate upon the lever E to throw the knuckle C to its full open position.

I propose to employ any suitable means for raising the pin G; but, in this instance, I show for this purpose, a rock shaft H supported in brackets L secured to the front of a car body, and the inner end of said shaft is provided with a forwardly extending arm which projects beneath, and is thus adapted to engage, a hook G⁵ with which the head of the pin is provided. It is apparent that, by rotating the shaft H by means of a handle provided at its outer end, the pin may be raised as required.

At its forward swinging end the arm E² of the lever E is provided with a depending

lug E', which operates in rear of the shank C² of the knuckle C, and within the recess C³ thereof, see Fig. 4, in actuating the knuckle C from its closed position, as shown in Figs. 3 and 6, to its open position, as shown in Fig. 7, Fig. 4 showing the knuckle C partially opened.

When the knuckle C is closed, as shown in Figs. 3 and 6, the depending lug E' lies within the recess C³, the body of the arm E² of the lever extending above the shank C², and within a recess C³ so that the jaw when closed does not exert any pressure whatever against the jaw-opening lever, but bears entirely against the curved wall A³ of the draw-head to which it is conformed, as will be understood from Figs. 6 and 7 of the drawing.

I claim—

- 20 1. A car coupling comprising a draw-head having its top wall provided with an upwardly projecting chamber and having a fixed jaw and a pivoted jaw and having the said jaw provided with a shank and in the rear face thereof at its upper edge with a recess extending to the upper face of the said shank, a jaw-opening lever having an upwardly projecting pivot portion extending within the upwardly projecting chamber of the draw-head, and having a forwardly projecting arm operating above the shank of the jaw and provided at its swinging end with a depending lug operating in the recess in said shank, the said opening lever having a second arm projecting laterally from its pivot portion, and a coupling pin having in its side facing said second arm of the opening lever a recess whose lower wall is inclined forming a cam surface for
- 25
- 30
- 35

engagement by said arm of the opening lever, said coupling pin being also adapted to secure and release the shank of the pivoted jaw, all substantially as and for the purpose set forth.

2. The combination of a draw-head, a pivoted jaw having a shank, a jaw-opening lever pivoted in the draw-head and having a forwardly projecting arm for operating the jaw shank and also having an arm extending laterally to its pivot, and a coupling pin arranged laterally to the pivot of the jaw-opening lever and having in its side, facing said pivot of the lever, a recess receiving the end of the laterally projecting arm of the opening lever and having said recess provided with a lower inclined wall forming a cam surface operating upon said lateral arm of the opening lever to actuate the same to open the jaw, and having the upper cam wall to operate upon said lateral arm of the opening lever whereby to re-adjust the latter, substantially as set forth.

3. A car coupling substantially as described comprising a draw-head, a pivoted jaw having a shank, a pivoted jaw opening lever having a forwardly projecting arm engaging with the jaw shank to open said jaw and also having a second arm projecting laterally to its pivot and a coupling pin having in its side facing the end of said second arm a recess receiving said end and having a lower inclined wall forming a cam surface to engage the said end of the second arm to operate the lever, substantially as described.

ORLANDO LEE ALBERTSON.
